(57) **CLAIM**

The ornamental design for a semi-round floor drain, as shown and described.

DESCRIPTION

FIG. 1 is a perspective view of a semi-round floor drain in accordance with the present invention;

FIG. 2 is a top plan view thereof;

FIG. 3 is a left elevational view thereof;

FIG. 4 is a bottom elevational view thereof;

FIG. 5 is a right elevational view thereof;

FIG. 6 is a front elevational view thereof; and,

FIG. 7 is a rear elevational view thereof.

The broken lines shown in the drawings illustrate portions of the semi-round floor drain and screws used with the semi-round floor drain that form no part of the claimed design.
